UNITED STATES PATENT OFFICE

LEONARD G. GRAY, OF DECATUR, ILLINOIS

BOTTLE OPENER

Application filed February 24, 1927. Serial No. 170,483.

My invention relates to that class of openers which are designed to remove the caps from capped bottles, and has for its object to provide a bottle opener of this type which 5 may be conveniently secured to the wall of a room.

Experience has shown that people, especially in hotel rooms, when they desire to open a bottle, make use of the door jambs 10 and furniture, thus causing considerable damage which it is impossible for the hotel proprietor to keep track of.

My invention has for its object to provide a bottle opener which can be attached to the 15 woodwork in the room, or the bathroom, so that there will be no occasion to deface or damage the woodwork.

My invention has for its further object to provide a construction so that when the bottle is opened, it will be in an upright position, thus avoiding any danger of spilling the 20 contents on the carpets or floor.

My invention has for its further object to provide in connection with the cap opener, 25 a torsional extractor to pull corks from bottles which are closed in that manner and to so arrange the extractor that both hands of the operator may be used to extract the cork, thus greatly increasing the ease of extraction.

30 My means of accomplishing the foregoing objects can be more readily understood by having reference to the accompanying drawings in which

Fig. 1 is a top view;

Fig. 2 is a front elevation;

Fig. 3 is a side view showing the support;

Fig. 4 is a side view showing the manner of opening bottles.

Similar reference numerals refer to similar 40 parts throughout the entire description.

As shown in the drawings, my improvement comprises a perpendicular portion 1, the lower part of which forms an inclined plane 2 which terminates in a hook portion 3 45 which is adapted to engage the edges of the cap of the bottle, as shown in dotted lines. The perpendicular portion 1 is preferably formed integrally with a base portion 4 which is formed by two circular members provided 50 with openings 5 and 6 for the reception of

wood screws 7 and 8. In the upper edge of the perpendicular portion 1, I form a slot 9 in which is mounted the ring 10 of the torsional extractor 11. The edges 12 and 13 of the slot 9 are then peened over sufficiently 55 to prevent the removal of the ring 10, yet permit it to freely slide around to any desired angle for use.

The operation of the device is as follows:

The screws 7 and 8 having been driven into the woodwork 14, (a fragmentary portion 60 of this only being shown, as it forms no part of my invention) the bottle is placed in the position shown in the full lines 15, the hook 3 engaging underneath the cap 16 on the bottle. The bottle is then moved into the position shown by the dotted lines 17. Obviously, by this operation, the cap will be pulled from the bottle, but the open bottle 65 will have assumed a vertical position, thus effectually preventing its contents being spilt should the bottle be corked instead of being capped, the torsional extractor is 70 screwed into the cork when the bottle may be grasped with both hands, thus doubling the available power required to extract the cork. 75

Having thus described my invention, what I regard as new and desire to secure by Letters Patent of the United States is:

A combined bottle cap and cork remover 80 comprising two circular members having central openings therethrough to receive wood screws to hold the extractor in position, a narrow outwardly extending portion connecting said members, the lower edge of said portion slanting upwardly and terminating in 85 a hook, the extractor being secured in position whereby when the cap is removed the bottle will be in a vertical position.

LEONARD G. GRAY. 90
